Primary Examiner — Marianne Pandozzi(74) *Attorney, Agent, or Firm* — Leanne Taveggia Farrell; Westman, Champlin & Koehler, P.A.(57) **CLAIM**

The ornamental design for a vessel holder, as shown and described.

DESCRIPTION

FIG. 1 is a first perspective view of a vessel holder showing our new design;

FIG. 2 is a second perspective view thereof;

FIG. 3 is a left side view thereof;

FIG. 4 is a right side view thereof;

FIG. 5 is a front view thereof;

FIG. 6 is a back view thereof;

FIG. 7 is a top view thereof; and,

FIG. 8 is a bottom view thereof.

The broken lines shown in FIG. 1 are included for purposes of illustrating environment and form no part of the claimed design. The broken lines shown in FIG. 8 are included for purposes of illustrating portions of the vessel holder and form no part of the claimed design.
